ABSTRACT

The invention makes it possible to reduce the number of parts required for the production of a rotatable catch in which no pivot is provided. A rotatable catch according to the invention comprises at least two semi-circular bolts each carrying at least two semi-circular orthogonal beads and two keeper housings receiving said bolts. It may be used for the closure of boxes, casings, doors, etc., and generally for the locking together of all parts coupled together or in contact side by side.

FIG.6

ROTATABLE CATCH

The present invention has for its object a rotatable catch permitting two members coming into contact to be immobilized with respect to each other.

The flat catch-bolt is already known, in which a toothed rack and a pinion convert the rotation of the operating knob to a to-and-fro movement of the bolt or latch in its keeper. A catch of this type thus comprises a number of parts and must essentially comprise a pivot about which the pinion rotates.

The catch according to the invention makes it possible to reduce the number of parts required for its production and in which no pivot is provided.

It is characterized in that it comprises at least one semi-circular bolt carrying at least two semi-circular orthogonal beads, one at the edge of the half-circumference, and the other laterally, so that the said bolt is held imprisoned with a single degree of freedom in a housing of corresponding shape formed in one of the parts to be locked together and, in consequence of the rotation which is given to it, becomes engaged in a symmetrical housing formed in the other part to be locked, this other housing then behaving first like a keeper and then like a bolt housing when the rotation is reversed.

According to one particularly advantageous form of construction, two semi-circular bolts are fixed together by their diameter when the parts to be locked are in contact, so that they constantly complete each other in this position of the parts.

Other characteristic features and advantages of the present invention will be brought out in the description which follows below, reference being made to the accompanying drawings, in which:

FIG. 1 is a front view of a catch according to the invention in its position of complete closure;

FIG. 2 shows a back view of two semi-circular bolts shown separately and placed together along their diameter;

FIG. 3 gives a perspective view of two parts intended to be locked together according to the invention, and being brought towards each other by pivotal movement, the bolts not being in position;

FIG. 4 shows a front view of the two parts when they have come into contact with each other;

FIG. 5 is a view similar to FIG. 3, with the bolts placed in position;

FIG. 6 is a view similar to FIG. 4, the two bolts being then associated together by their diameter;

FIG. 7 is a profile view of a bolt.

In the form of construction shown, the rotatable catch according to the invention comprises two semi-circular identical bolts 1. Each bolt is thus limited by a half-circumference c and a diameter d . A bead 2 is provided on the half-circumference and another bead 3 along a circular arc, forms a projection at right angles and laterally on the back 4 of the bolt. When the two bolts are placed together along their diameter, the two beads 2 become joined together, as do also the two beads 3.

A semi-circular housing 5 which serves alternately as a bolt housing and as a keeper is formed in each of the parts A and B which come into contact so as to be locked together. Each housing having a shape corresponding to each of the bolts is hollowed with a groove 6 in order to receive a bead 2 of the bolt and a groove 7 to receive a bead 3 on the bolt. When the housings

5 are brought together due to the meeting of the parts A and B, the two grooves 6 become joined together as do also the two grooves 7 (see FIG. 4).

In the form of construction shown, the parts A and 5 B come into contact with each other by pivotal movement in the direction of the arrows f_1 (see FIGS. 3 and 5).

Previously, a semi-circular bolt 1 has been introduced into each semi-circular housing 5. This introduction is effected by presenting the bolt laterally to the housing, diameter to diameter, and turning the bolt towards the interior of the housing, in such manner that the bead 2 passes into the groove 6 and the bead 3 into the groove 7. Each bolt in this way becomes imprisoned 15 in a housing, while retaining however one degree of freedom (see arrows f_2 , f_3 , FIG. 6).

When the parts A and B come into contact with each other, the diameter d of the bolts is in the alignment of the edge T of the parts A and B, and no locking action is obtained (see FIG. 6), but as soon as the bolts are rotated, either in the direction of the arrow f_2 or in the direction of the arrow f_3 , a locking action is obtained (see FIGS. 6 and 1). In this case, the bolt housing downstream of each bolt in progressive movement becomes a keeper for that bolt.

On its visible face, opposite to that carrying the bead 3, each bolt is provided with an operating projection 8, in such manner that the operating projections of the two bolts come together along the line of contact so 30 that they can be gripped together.

Each bolt may comprise an extension in the form of a half-mushroom, of which the foot 9, coupled to the back 4 of the bolt, and the flat head 10 are respectively received in a semi-circular notch 11 formed in the centre of the housing 5 and in a semi-circular groove 12 formed in the part.

As may be understood from the preceding description, the rotatable catch according to the invention is particularly advantageous due to its simplicity; two keeper housings 5 and at least one bolt 1 enable it to be produced. No pivot is provided so that this simplicity of construction is accompanied by simplicity of mounting and easy operation free from failure. The housings and bolts may furthermore be made from plastic materials, the self-lubricating properties of which are well known, which further facilitates the operation of the catch.

The rotatable catch according to the invention finds 50 an application whenever it is necessary to fasten together two pieces which come into contact, either by pivoting or by translation or by sliding, of at least one of these parts. It may be used for the closure of boxes, casings, doors, etc., and generally for the locking together of all parts coupled together or in contact side by side.

A stud 13 may be provided on the periphery of the bead 2 of each bolt so as to become engaged in a double abutment 14 formed in the bottom of each groove 6 and thereby producing a certain blocking effect on the bolt.

It will of course be understood that the present invention has only been described and illustrated as a preferred example, and that equivalents may be introduced into its constituent parts without thereby departing from the scope of the said invention, as defined in the appended claims.
